UNITED STATES PATENT OFFICE.

NATHANIEL W. WOODBURY, OF BEVERLY, ASSIGNOR TO SWAIN, FULLER & CO., OF LYNN, MASSACHUSETTS.

SOLE-SHAPING MACHINE.

SPECIFICATION forming part of Letters Patent No. 309,674, dated December 23, 1884.

Application filed October 13, 1884. (No model.)

To all whom it may concern:

Be it known that I, NATHANIEL W. WOODBURY, of Beverly, in the county of Essex and State of Massachusetts, have invented certain new and useful Improvements in Sole-Shaping Machines, of which the following is a specification.

My invention relates to improvements in machines in which shoe-soles are shaped by being placed on a last which is raised and forced against an upper form, and more particularly to improvements in the machine for shaping the soles of boots and shoes shown and described in Letters Patent No. 230,187, granted to J. B. Johnson, July 20, 1880. In that machine the slide and its last are raised by a treadle, and a rotary cam mounted on the cross-head of the toggles is then turned to clamp the sole firmly between the last and the fixed form.

One object of my invention is to dispense with the rotary cam and the second movement necessitated thereby; and to this end my invention consists in a tumbler-cam arranged between the toggles and the slide or last-holder and operated by the treadle so as to raise the last and clamp the sole between the last and the form.

Another feature of my invention relates to the toggle-operating device; and it consists in a grooved cam mounted loosely on a rotating shaft, the cam being caused to revolve at the proper time to shift the pin of the toggle-joint by means of a clutch splined on the shaft and connected to a trip-treadle, by means of which the clutch may be thrown into or out of connection with the cam, as desired.

In the Johnson machine above mentioned the toggles are operated by means of dogs provided with a lever, by means of which they can be thrown into the path of a reciprocating notched bar, the operation requiring an extra movement of the attendant.

In the accompanying drawings, which illustrate a Johnson sole-shaping machine with my improvements embodied in the best way now known to me, Figure 1 is a front elevation showing the parts in two positions. Fig. 2 is a section on line *x* *x* of Fig. 1, and Fig. 3 is a section on line *y* *y* of Fig. 1.

A is the form. B is the slide or last-holder

mounted on the cross-head *b*, and adjustable vertically thereon by means of the screw *b'* and the gears *b²* *b³*. D D' are the toggle-levers. The upper one, D, carries a cross-head, *d*. The lower one, D', is jointed to the frame at *d'*. A tumbler-cam, F, is jointed at one end to the cross-head *d*, and at its other end to a rod, *h*, connected to one end of the treadle-lever H. The cross-head *b* rests on the upper surface of the cam F, and is raised or lowered by turning the cam F by means of the lever H and rod *h*. After the last reaches the height to which it can be raised by the cam F, the toggles D D' are brought into action (to give the pressure requisite for setting the sole to shape) by throwing the clutch I, splined on the revolving shaft *i*, into connection with the cam *i'*, having an oblique groove, *i²*, formed in it, and into which groove the joint-pin *d²* of the toggles enters. The clutch I is thrown by means of a bell-crank lever, one arm, *i³*, of which is connected to the clutch. A treadle, *i⁴*, is provided with a hooked arm, *i⁵*, the hook of which engages the other arm, *i⁶*, of the bell-crank lever. On depressing the treadle *i⁴* its hooked arm *i⁵* will engage with the arm *i⁶* of the bell-crank lever and cause the clutch to connect with and revolve the cam F. The cam F, if constantly revolved, would impart a reciprocating motion to the joint-pin of the toggles; but as the pressure on the sole should continue for some time, the toggles must remain in their extended position during that time. For this reason the hooked arm *i⁵* is thrown off from the arm of the bell-crank lever, immediately after the clutch engages with the cam, by means of a tripper, *i⁷*, coming in contact with a stop, *i⁸*. The friction between the clutch and the cam is sufficient to hold the clutch and cam together for half a revolution of the shaft *i*, during which the toggles are fully extended. As the shaft *i* continues to revolve, the friction between the cam and clutch ceases just as the joint-pin *d²* would commence to move in the opposite direction. At this moment the clutch is thrown off from the cam by means of a spring, *i⁹*. The cam now ceases to revolve and remains in position to open the toggles when the treadle *i⁴* is again depressed. By arranging the treadles one above the other, as shown, the entire op-

eration of raising and forcing the last against the form can be accomplished by one movement of the foot. To separate the platens, the treadle *i*⁴ is first depressed to connect the clutch and cause the cam to make a half-revolution, and thereby relieve the pressure of the toggles, and the cam F is then turned back by raising the treadle-lever H.

I claim as my invention—

- 10 1. In a sole-shaping machine, the combination, with the last-holder and the toggle-levers, of an interposed tumbler-cam and the actuating means, substantially as described.

2. In a sole-shaping machine, the combination, with the joint-pin of the toggle-levers, of a grooved cam, a clutch, a lever whereby the clutch may be thrown into connection with the cam, and a tripper by means of which the clutch is released, all arranged to operate substantially as described.

NATHL. W. WOODBURY.
